UNITED STATES PATENT OFFICE

WILLIAM H. WASCHER, OF FLINT, MICHIGAN

INDICATING DEVICE

Application filed October 4, 1928. Serial No. 310,250.

This invention relates to indicating devices and particularly to such devices as are suitable for use in indicating the street number of residences, or like uses, the principal object being the provision of a device of this kind which will be visible either day or night.

Another object is to provide an illuminated indicating device in which the illuminating means will be kept constantly burning.

10 Another object is to provide a device of the type described that will be constantly illuminated, but in which the illuminating means will be ineffective as far as illumination is concerned in daylight.

15 Another object is to provide an illuminating device of the type described in which the illuminating means are supplied with power from a step-down transformer floating on the ordinary house-lighting circuit.

20 Another object is to provide a device of the type described in which the illuminating means derives its power from the transformer employed in connection with the usual bell-ringing circuit conventionally employed in 25 residences and the like.

Another object is to provide a new and novel construction for an illuminating indicating device.

A further object is to provide an illuminated 30 indicating device comprising a container provided with a readily detachable face, the face being formed by a pair of transparent plates overlying each other and enclosing between them a stencil plate and a 35 light diffusing member.

The above being among the objects of the present invention, the same consists in certain features of construction and combinations of parts to be hereinafter described with 40 reference to the accompanying drawing, and then claimed, having the above and other objects in view.

In the accompanying drawing which illustrates 45 a suitable embodiment of the present invention, and in which like numerals refer to like parts throughout the several different views,—

Fig. 1 is a more or less diagrammatic partially 50 broken face view of my indicating de-

vice illustrating the electrical circuit for the same.

Fig. 2 is an enlarged partially broken face view of my indicating device.

Fig. 3 is a sectional view taken on the line 55 3—3 of Fig. 2.

The idea of providing an illuminated indicating device for indicating street numbers and the like is in itself old, but so far as I am aware, such devices have not come into wide use due to the attention which is necessary in connection with those designs already proposed, and also because of the relatively great cost involved not only in the original investment but in the cost of supplying power to the same. Furthermore, most of such devices already proposed have not been equally efficient for both day and night use. The present invention obviates the disadvantages of the constructions heretofore suggested in that it not only provides a construction that is economical in its initial cost, which employs a negligible amount of power for its continued operation, but is equally efficient either in daytime or at night.

75 Referring to the accompanying drawing it will be noted that the device itself comprises a pan-like container 10 open on one side only and having the margins of the open side turned over as at 11 around a wire such as 12 so as to form an outwardly extending flanged or beaded edge. Within the container is a base 13 which receives a suitable electric bulb 14. The open side of the container 10 is closed by two glass plates 15 and 16 which 80 overlie the open face of the container and which are secured thereto by a frame provided with a relatively narrow flange 17 overlying the sides of the outer face of the plate 16 and extending around the margins of the plates 15 and 16 and engaging the same, and provided with in-turned flanges 18 along the sides which resiliently embrace the marginal side flanges 11 of the container and resiliently clamp the transparent plates 15 and 16 85 against the face of the flanges 11. Between the plates 15 and 16 are positioned a stencil plate 19 and a light diffusing plate 20. The plates 15 and 16 are preferably of clear glass. The stencil plate 19 may be of any opaque ma- 90 95 100

terial or suitable translucent material which will not permit a too ready passage of the light therethrough, and the plate 20 may be made of any suitable material preferably of a translucent type such as colored crepe paper or any other like material which will cause suitable diffusion of the light from the bulb 14 before the light is transmitted through the openings in the stencil plate 19. The 10 plates 19 and 20 are preferably separable from each other and from the glass plates 15 and 16 so that any color of the diffusing plate 20 and any suitable stencil design on the plate 19 or color thereof may be furnished with 15 any device that may be sold, although they may be cemented or otherwise secured in place when desired. The stencil plate 19 is preferably of a light color such as white and the plate 20 of a relatively dark color which 20 will set out the markings in the stencil plate with clearness and exactness in daylight but which, when viewed at night through the markings in the stencil plate, will clearly and easily disclose such markings. It will, of 25 course, be obvious that at night the stencil plate will appear black and the markings therein will appear as of the color of the plate 20, while in the daytime the stencil will appear white or any other color with which 30 it may be finished and the markings therein of the color of the plate 20, the illuminating means in the daytime being of insufficient brilliancy to cause the light to be apparent through the markings in the stencil plate.

35 The clamping frame which secures the plates 15, 16, 19 and 20 to the container 10 ordinarily clamps the plates to the container with sufficient firmness to prevent possible entrance of rain into the interior of the container, but should any rain find its way back of the lower face flange 17, the same may escape from the frame through openings such as 41 formed in the lower side face of the frame.

45 In order that this device require substantially no attention during its operation I keep the bulb 14 constantly burning so that there is no necessity of turning off the light in the daytime, and in order that this constant burning of the light will not entail an undue expense for its illumination, I employ a low voltage bulb preferably of the six-volt type. The source of power for the bulb 14, in order to reduce the cost of the same to 50 a minimum, is obtained in the following manner. As is generally known substantially every residence at the present time is provided with an electric light circuit of approximately 110 volts. These circuits are invariably of the alternating current type, and in Fig. 1 I denote the two sides of the circuit as 22 and 23 respectively. In residences so provided the door bell circuit includes a step-down transformer such as 24 interposed between the two sides of the lighting circuit

22 and 23, such transformer stepping the current down to approximately six volts. These transformers draw so little power from the lighting circuit that they may be said to substantially float on the same. The 70 transformer 24 is connected by a lead 25 to a bell or buzzer 26 and in turn is connected by a lead 27 to one or more push buttons 28 which in turn are connected by leads such as 29 back to the other side of the transformer 75 so that upon contact through the button 28, the bell or buzzer 26 is caused to operate. In accordance with the present invention I employ the bell ring transformer 24 as the source of power for the bulb 14 by connecting it up to the same with leads such as 30 and 31 and without the employment of a switch of any kind in such leads. The result is that the cost of constantly burning the bulb 14 is so small as to be substantially negligible. 80

85 From the above it will be apparent that by the employment of the present invention I have provided an illuminated indicating device which is equally visible at day or night, that is economical to manufacture, whose parts are readily interchangeable, which demands a minimum of service and attention, and which is economical to maintain.

90 95 Formal changes may be made in the specific embodiment of the invention described without departing from the spirit or substance of the broad invention, the scope of which is commensurate with the appended claim.

100 What I claim is:

An indicating device comprising a container having an open face, a closure for said open face comprising a stencil plate and a translucent light diffusing plate, said light diffusing plate being disposed inwardly of said stencil plate, said light diffusing plate being visible through the stencil markings in said stencil plate and being of a darker color than that of the outer face of said stencil plate, and a source of illumination within said container of sufficient intensity to visibly illuminate said stencil markings in darkness but ineffective to visibly illuminate the same in daylight. 110
